GRID-TYPE GRILLE

Lee B. Green, Lakewood, Ohio, assignor to The
Globe Machine & Stamping Company, Cleve-
land, Ohio, a corporation of Ohio

Application June 21, 1934, Serial No. 731,663

7 Claims. (Cl. 189—82)

My invention relates to metal grilles of the general type in which relatively transverse sets of blades and cross-bars are first slidably inter-engaged with each other to prevent a shifting of the blades with respect to the cross-bars in the general plane of the grille, and in which the blades are thereafter fastened to the cross-bars so as to prevent the blades from sliding out of their slidable engagement with the cross-bars.

10 In my copending application #723,948, filed May 4, 1934 on a Grid-type metal grille, I disclosed a grid-type grille of this general class, in which each blade presents loop portions behind the common rear surface of the cross-bars, and in which each blade is anchored to the cross-bars by an anchoring rod extending through the said loop portions of the blade.

While the grid-type grille of my said application lends itself admirably to the manufacturing of automobile radiator grilles presenting ornamental appearances of varying designs, I have found my there disclosed construction to have the following limitations, the overcoming of which is among the main objects of my present invention:

20 (1) The cost of the anchoring rod associated with each blade of the grille, together with the labor required for inserting this rod add undesirably to the manufacturing cost of the grille.

25 (2) When a blade is to be anchored to the cross-bars by an anchoring member which extends behind the cross-bars, the blade usually must be considerably wider than the cross-bar, thereby requiring more metal for the blade than might otherwise be needed.

30 (3) When each blade is of a uniform width throughout its length, as is commercially desirable, and the cross-bars are to present their forward edges at a uniform distance rearward of the forward edges of the blades (as is desirable for the sake of appearance), the blades must be of a uniform width throughout their length unless the cross-bars adjacent to wider blade portions are indented at their rear to such an extent as to weaken them.

35 Consequently, the grille construction of my prior application does not readily lend itself to an adequate concealing of the apron underhanging the lower portion of an automobile radiator grille in which the lower portions of the blades slope forward downwardly, since this part of the grille is so far below the eyes of an observer that mud collected on the said apron can readily be seen through the grille unless the cross-bars in the lower part of the grille have a considerably

greater width than that required in the higher parts of the grille.

40 (4) The rearwardly looped blade construction needed for the grilles disclosed in my said co-pending application preferably requires the use of resilient metal for the blade, in order that the resiliency of the metal will insure the firmness of the anchoring of these blades to the cross-arms; and in practice such a looped blade desirably has to be formed from a strip of metal bent about 45 its medial line, which strip of metal must initially be of more than double the width of the finished blade. Consequently, my said prior construction does not readily lend itself to the use of blades consisting of generally flat strips such as could 50 be manufactured much more cheaply.

45 Illustrative of the manner in which my here presented invention overcomes the above recited limitations of my previously disclosed grid type grille,

55 Fig. 1 is a perspective view of a portion of a grille embodying my invention, including cross-bars of varying widths and single-thickness blades anchored to the cross-arms by the ornamenting tubes which are slid over the forward portions of the blades.

60 Fig. 2 is an enlarged perspective view of portions of two of the cross-bars of Fig. 1 and of a part of a blade slidably interlocked with these cross-bars, as they appear before the slotted ornamenting tube (of which a fragment is also shown in Fig. 2) is slid over the forward portions of the blade to anchor it to the cross-bars.

65 Fig. 3 is a fragmentary horizontal section taken along the line 3—3 of Fig. 1.

70 Fig. 4 is a section allied to Fig. 3, showing the use of a similarly constructed blade and anchoring tube in connection with a cross-bar having a frontal recess which affords a wider bearing for the said tube.

75 Fig. 5 is a section allied to Fig. 4, showing a different cross-section of the anchoring tube and of the frontal recess in the cross-bar.

80 Fig. 6 is a section allied to Fig. 3, showing the use of a blade formed of a metal strip doubled along its longitudinal center line.

85 Fig. 7 is a section, also allied to Fig. 3, showing the rearward half of the blade as corrugated, so as to insure its bearing against both side walls of the slot in the cross-bar regardless of variations in the exact width of this slot.

90 Fig. 8 is a fragmentary perspective view of a grille in which certain blades are clamped to the cross-bars by ornamenting tubes after the manner of Figs. 1 and 3, and in which intervening

and relatively narrower blades are clamped to the cross-bars by lugs each of which is formed from a rear-edge portion of a cross-bar and engages the rear edge of one of the narrower blades.

5 Fig. 9 is an enlarged and fragmentary horizontal section, taken along the upper face of the upper cross-bar of Fig. 8, showing the anchoring lug which clamps one of the narrower blades to this upper cross-bar.

10 Fig. 10 is a fragmentary perspective view in which every other blade is generally U-sectioned and anchored to forwardly recessed portions of the cross-bars by an ornamenting tube, and in which each alternate blade is anchored after the 15 manner shown in Fig. 9.

Fig. 11 is an enlarged side elevation of the grille part shown in Fig. 10, taken from the right-hand side of Fig. 10.

20 Fig. 12 is an enlarged horizontal section taken along the line 12—12 of Fig. 10.

Figs. 13 and 14 are enlarged perspective views of portions of the two types of blades shown in Figs. 10 to 12.

25 In the parallel bladed embodiment of Figs. 1 to 3, each horizontal cross-bar C has parallel and spaced slots S extending forwardly into it, desirably across somewhat more than half of the width of the cross-bar, each of which slots preferably is of a width closely corresponding to the thickness 30 of the strip of metal from which a blade of a grille is formed.

35 Each of the upright blades B has horizontal slots s extending rearwardly into it and corresponding closely in thickness to the thickness of the cross-bars C, the depths of these slots s being such that when the blades are slidably assembled with the cross-bars (after the manner of the partitioning strips in an egg carton or a candy box) the blades will project forwardly beyond the common 40 frontal surface of the forward edges C¹ of the cross-bars. The forwardly projecting blade portions between consecutive cross-bars are bent (alternately in opposite directions) so as to constitute forwardly diverging fingers B¹; and after the 45 blades and cross-bars have thus been assembled into a grid, with the bottoms of the slots S in the cross-bars bearing against the bottoms of the slots s in blades, I slide over the said diverging black fingers B¹ a rearwardly longitudinally slotted tube 50 T of such a size as to bear rearwardly against the adjacent forward edges C¹ of the cross-bars and forwardly against portions of the said blade fingers.

55 Each tube T preferably is formed of resilient metal, thereby permitting it to expand sufficiently to compensate for the slight irregularities which occur in the commercial manufacture of the slotted blades and cross-bars, thereby drawing the corresponding blade forward to press the bottoms 60 of the slots in the blade against the bottoms of the slots in the cross-bars, so that the tubes co-operate with the recited proportioning of the said slot widths to hold the blades rigidly assembled to the cross-bars without requiring auxiliary fastening means.

65 Each such tube T may be of a bright metal contrasting with both the blades and the cross-bars—as for example, of chrome-plated steel or stainless steel—so as to enhance the ornamental appearance of the grille.

70 In assembling such a grille, the initial slidable interfitting of the blades with the cross-bars is a simple and speedy operation, and each ornamenting tube can quickly be slid forcibly over the frontal fingers on a blade even when this blade

has its forward edge curved as shown in Fig. 1. Moreover, the firmness of the resulting assembly is not affected by considerable variations in the width of the cross-bars, so that in the forwardly curving lower part of a grille the lower cross-bars C² may (for example) be wider than the upper cross-bars C, as shown in Fig. 1.

75 With each tube T adequately resilient, a mere engagement of the slit edges in the tube with the forward edges C¹ of the cross-bars, as shown in Fig. 3, has been found sufficient to insure the rigidity of the grille, particularly when the slots in the cross-bars correspond closely in width to the thickness of the rearward portions of the blade.

15 However, in the commercial manufacture of such grilles, I desirably provide each cross-bar at its forward edge with recesses R alining axially with the medial planes P (Fig. 4) of the slots in the cross-bar, so that each tube will have portions of considerable width (at respectively opposite sides of its slit) bearing against parts of such a recess, thereby insuring the desired rigidity even if the blade fits the adjacent slit in the cross-bar rather loosely.

20 Moreover, the (horizontal) cross-sectional shape of each recess R may be varied so long as the cross-section of the tube adapts the tube to bear adequately against the wall of the recess, as shown for example by the semi-hexagonal 30 section of the recess R¹ in Fig. 5 and the shaping of the tube T¹ which presents two portions bearing flatwise against portions of the wall of this recess.

25 However, instead of using longitudinally spaced 35 portions of each blade to afford the diverging fingers, the blade may have its frontal portion doubled back on itself and then bent at right angles to the major portion of the blade, so as to present a "T-head" 3 as shown in Fig. 7 straddled 40 by the anchoring tube. And if the metal of the blade is so thin as to make it difficult to form slots of a closely corresponding width in the cross-bars, the rearward part of the blade may be longitudinally corrugated, as shown at 4 in Fig. 7 so 45 as to bear against both side walls of the slots.

30 So also, the same principle of locking a blade to the cross-bars by a slotted tube which straddled a widened blade portion spaced forwardly from the cross-bars may be employed (as in Fig. 6) 50 with a blade 5 formed of a quite thin strip of metal folded along its medial longitudinal line and having the free edges of the strip bent away from each other, to present diverging fingers 6. This figure also shows still another cross-section 55 of the anchoring tube T².

35 Moreover, it is not essential to my invention to have every blade project forwardly beyond the cross-bars and clamped to the cross-bars by an ornamenting tube, since the heretofore described 60 assembly may be used only in connection with certain blades of the grille.

40 For example, Fig. 8 shows a fragment of a grille in which only two blades B are clamped to the cross-bars C by slotted tubes T after the manner 65 of Figs. 1 and 3. The intervening two blades 6 present their forward edges flush with the forward edges of the cross-bars, each of these blades 6 being clamped to each cross-bar by de-forming a rearward part of that cross-bar to project into a slot of that cross-bar and to engage the rear edge of this cross-bar as shown on an enlarged scale in Fig. 9, thus changing the appearance of the grille considerably from that of Fig. 1 and considerably reducing the cost of the grille. 75

So also, the appearance of a grille embodying my invention may be further varied by using generally U-sectioned and forwardly open blades 1, formed as in Fig. 13 to present frontal fingers 8, each such blade being anchored to the cross-bars by a slotted tube T as shown in Fig. 12, so that the anchoring is on the same principle as shown in Fig. 4. Figs. 10 and 12 also show the use of intervening narrower and entirely flat blades 9 (formed as in Fig. 14) anchored by lugs C⁴ on the cross-bars, thus contrasting all the more from the shape and appearance of the wider blade members, each of which comprises a blade 1 and an anchoring tube T. Thus my invention readily lends itself to the construction of a large variety of grille designs, in addition to eliminating the cost of the anchoring rods required for the grilles disclosed in my said copending application #723,948.

20 However, while I have heretofore described my invention in connection with grilles having upright blades and horizontal cross-bars, it will be obvious that the directions in which these relatively transverse members extend is immaterial. 25 So also, the spacings between the blades, and between the cross-bars can be greatly varied, as shown for example by a comparison of Fig. 9 with Fig. 1 or Fig. 10.

Moreover, while I have heretofore described my invention in connection with embodiments including numerous desirable details of construction and arrangement, it should be obvious that these could be varied in many respects without departing either from the spirit of my invention 35 or from the appended claims.

I claim as my invention:

1. An upright grille comprising a set of spaced upright blades each provided at its forward edge with forwardly diverging fingers and each having slots extending rearwardly into it; a set of spaced horizontal cross-members each having slots, corresponding in their spacing to that of the blades extending forwardly into it, the said cross-members being slidably interfitted with the blade members so that each slot in the cross-member houses a portion of a blade contiguous to the bottom of a slot in that blade; and a set of longitudinally slotted tubular ornamenting members extending in front of the cross-members and each straddling the diverging fingers on one of the blades; the tubular members having portions thereof bearing against the members of one of the said sets to clamp the bottoms of the slots in the cross-members against the bottoms of the slots in the blades.

2. An upright grille comprising spaced upright blades each provided at its forward edge with forwardly diverging fingers and each having slots extending rearwardly into it; spaced horizontal cross-bars each having slots, corresponding in their spacing to that of the blades, extending forwardly into it, each cross-bar having its forward edge provided with recesses alining with the slots in it; the cross-bars being slidably interfitted with the blades so that each slot in a cross-bar houses a portion of a blade which is behind the bottom of a slot in that blade; and a set of longitudinally slotted tubular ornamenting members

extending in front of the cross-bars and each hooked over the diverging fingers on one of the blades, each tube bearing rearwardly against recessed edge portions of the cross-bars so as to clamp the bottoms of the slots in the cross-bars against the bottoms of the slots in the blades.

3. An upright grille comprising upright blades each having spaced horizontal slots extending rearwardly into it, horizontal cross-bars each having spaced upright slots extending forwardly into it, the said blades and cross-bars being slidably assembled with the bottoms of the slots in the blades bearing against the bottoms of the slots in the cross-bars, each blade being formed so that the parts thereof which extend between consecutive slots in that blade afford forwardly diverging fingers spaced forwardly from the forward edge portions of the cross-bars adjacent to that blade; and rearwardly longitudinally slotted tubes each straddling the said fingers on one of the blades, each such tube having portions bearing forwardly against the fingers straddled by it and rearwardly against the cross-bars, so as to interlock the blades rigidly with the cross-bars.

4. A grille as per claim 1, in which the consecutive fingers on each blade extend alternately in opposite horizontal directions.

5. A grille as per claim 1, in which each of the said fingers reaches from one slot in the blade to the next slot, and in which the said fingers extend alternately in relatively opposite horizontal directions from the medial plane of the blade part behind the said fingers.

6. An upright grille comprising a set of spaced parallel and generally flat blades each having slots extending rearwardly into it; spaced horizontal cross-bars each having slots extending forwardly into it, the said slots corresponding in their spacing to that of the blades and in width to the over-all effective thickness of the blade parts behind the slots in the blades; the cross-bars being slidably interfitted with the blades so that each slot in the cross-arm houses a portion of a blade behind the bottom of a slot in that blade member, the depths of the slots in the said blades and cross-bars being such that each blade has its frontal part projecting forwardly beyond the surface in which the forward edge portions of all cross-bars which are adjacent to the blades are disposed, and each such frontal part of a blade being of greater thickness than the width of a rear blade part; and a set of rearwardly longitudinally slotted tubular ornamenting members extending in front of the cross-bars and each having rearward portions thereof bearing forwardly against the said frontal parts of a blade and rearwardly against the cross-bars, so as to clamp the bottoms of the slots in the cross-bars against the bottoms of the slots in the blades.

7. A grille as per claim 1, in which each blade is formed of a strip of metal bent to a generally U-shaped cross-section and presenting the U-back at the rear of the blade, and in which the said diverging fingers are respectively formed from forward portions of the two U-shanks of the blade.

LEE B. GREEN.
